LIGHT-ELECTRONIC SCENT RELEASE

Emery I. Stern, Jackson Heights, N. Y.

Application October 13, 1947, Serial No. 779,630

2 Claims. (Cl. 88—16)

1

This invention relates to scent distribution by light activated electronic means, and is an improvement on my co-pending application for Releasing and Synchronizing Methods and Means for Scents, Ser. No. 561,751, filed November 3, 1944, now abandoned.

My present invention provides different means for scent distribution from those described in my said co-pending application, which means are better adapted in certain conditions and which also do not include said mechanical means and operate directly by simple electronic agencies controlling the starting and stopping of the release of predetermined scents.

Another object of this invention is to provide a novel way of releasing and vaporizing scents carried by compressed or liquified gaseous mediums.

Still further objects of this invention will be apparent as the specification of the same proceeds, or will be pointed out therein.

In the drawings forming a part of this specification and accompanying the same:

Fig. 1 is a diagram showing my method and means for selecting and distributing scents to accompany a motion picture shown in an auditorium, said method using electronic means acted upon by light rays;

Fig. 2 is a fragmentary view of a portion of a film prepared for said light effects, certain light conducting rods such as transparent plastic, also being shown in section, as indicated on the line 2—2 in Fig. 1;

Fig. 3 is a diagram of a modification of my invention, and

Fig. 4 is a diagrammatic section showing a scent film and its action on the transparent plastic or like rods, as well as its connection to the picture film which it is to accompany;

Fig. 5 is a fragmentary detail, on a larger scale, of the selector film used in this modification of my device;

Fig. 6 shows still another modification.

Referring now to the embodiment shown in Figs. 1 and 2, the numeral 10 indicates a light source which is intended to control the selection of the scents accompanying the showing of a motion picture film.

A parabolic mirror 11 is arranged for the light source 10, so that the rays of said light source will all be thrown in the straight direction indicated in an imaginary manner at 12, and in parallelism with the axis of the parabolic mirror.

At 13 the scent selector film is shown which preferably will cover the width of the opening

2

of the parabolic mirror 11, and will travel along the front thereof, that is, in a direction perpendicular to the plane of Fig. 1.

Apertures 14 are provided in the film 13 (Fig. 2), the rest of the same being entirely opaque. Said apertures are arranged in longitudinal rows on the film 13 covering the whole width thereof, said rows preferably being equidistantly placed, as indicated at 15.

It will be understood that the selector film 13 will be operated in synchronism with the picture film, the showing of which is to be accompanied by release of appropriate scents, at the respective scenes thereof, when such a scent release is desirable.

The synchronous driving of the picture film (not shown) and of the scent control film 13, may be accomplished by various ways, well known to those versed in this art, one of which is described in my co-pending application No. 561,751, now abandoned.

As the scent controlling film 13 passes in front of the opening 11a of the parabolic mirror 11, the rows of openings 14 will pass in registering relation with respective light guiding rods 16, preferably made of a specific plastic material such as methyl methacrylate, well known in this art under the name of "Lucite" or any other similar material, and when an aperture 14 arrives in the registering relation with such a rod, as indicated at 14a and 16a, a respective light beam 12a will be guided through the rod and will strike a photo-electric cell relay switch, indicated by the numeral 17a. A plurality of such photo-electric cell relay switches 17 are arranged in front of the rods 16, each one registering with a respective rod.

The various scents are provided ready for release at the desired moment, in a specific manner, in containers 18.

Obviously, each photo-electric relay switch 17 will control one respective scent, but in Fig. 1, I show only four containers for four different scents, for the sake of clarity, and larger details in the diagram of said figure.

Obviously, the arrangement for the other relay switches than the four right hand ones shown as connected to the four containers, will be the same with additional containers.

In containers 18 I provide the scents in a novel manner for release and distribution in a theatre or other auditorium, and the scents will be enclosed in the containers dissolved or mixed in a gaseous medium or in a liquified state, under a desired high pressure, and a pipe 19 is provided

for each container whereby a gaseous medium may escape carrying the scent with it under a desired pressure and with a desired speed, in a highly distributed atomized condition. Of course, normally the containers 18 are closed and the gas stream, with the atomized scent, can escape through the pipes 19, only when the respective closure valve of the container is opened. The closure valves are generally indicated at 20, and they are any usual type, well known in this art, and operated by an electric solenoid 21, and it will be seen that when the solenoid 21 is energized, valve 20 will be opened, and the respective scent will be blown through a pipe line 18 into an air current carrying distribution pipe or duct 22, similarly as has been described in my said co-pending application, and as will be further described hereinafter.

I also insert a regulating valve 23 into the pipe 19 for each scent container 18, whereby the speed and amount of the gas and scent material released upon the opening of the valve 20, may be adjusted.

As has been mentioned, the solenoids 21 normally are inactive, but they are inserted into respective electric circuits controlled by the photo-electric relay switches 17.

For example, taking the switch 17a, the same will close a circuit having a branch 24 going to the respective solenoid 21a, and another branch 25 is joined into one, let us say the outgoing, conductor 26, for the source of electric power 27. The electric current going through the solenoid 21a will exit therefrom through the conductor 24a, and will be joined by the same into the other, let us say the return, conductor 28 of the electric power.

It will be seen that when the photo-electric cell 17a is activated and closes the relay switch, it will close the circuit of the solenoid 21a, thereby opening the valve 20a and releasing the respective scent 18a, which, through the pipe 19a will blow into the scent distributing duct 22.

The photo-electric relay switch 17a will be closed any time when an aperture 14 passes in registering relation with a rod 16a, as indicated in Fig. 1, and, in the position of the device there indicated, the scent 18a will be released, blown into the duct 22, which duct is indicated as entering a larger duct 29 through which a diluting and carrier air current will travel, arrows 30, induced by the compressor or blower 31, or by any other source for the same. This duct 29 is branched off in any desired manner in the auditorium and the scent distributed and released at various places thereof in any appropriate manner, as will be understood.

An air compressor 32 or other source of compressed air is provided feeding the tank 33 so that a substantially stationary air stream will blow through the primary scent receiving pipe or duct 22, as indicated by the arrow 34.

The scent in this manner, will receive a predetermined adjusted dilution with air, and its speed will also be adapted to be so regulated as to be imperceptible for the audience. The air current may be heated, when necessary, also in a predetermined manner. The final mixture of scent carrying gas, and primary and secondary diluting air, will be released, and will act on the respective senses of the audience with entirely identical characteristics as the air present in the auditorium, so as to be practically unnoticeable when the scent is spreading except by the sensory organ.

As will be seen, the motion picture film will be run and keenly observed, and the various scenes and their distances in feet, or in time of running, carefully noted, to see when a certain scent will be desirable to be released, and thereby enhance the effect of the respective scene on the audience, whereupon the scent controlling film 13 will be made, apertures 14 being provided according to the times or distances found. Obviously, the scent controlling film 13 need not be run with identical speed to the picture showing film. The only factor needed is that they should be run synchronously, while film 13 may be run much slower, which most probably will be better in actual practice.

Any time an aperture 14 arrives in front of a respective light beam guiding rod 16, the registering photo-electric cell relay switch 17 will activate its scent 18, which will be distributed in the audience in a substantially unobservable manner, except for the scent, itself, as has been indicated hereinbefore.

In cases where it is necessary, a neutralizing agent may be distributed after every scent, and for such purpose the neutralizing agent, or several agents, if needed, will be contained in appropriate containers 18, and will have their own respective apertures 14 and relay switches 17.

The embodiment of my invention for distributing scents through light beam control, as shown in Fig. 1, has limitations. For every scent another row of apertures must be provided, and, naturally, the width of the control film 13 is limited, therefore the number of scents which may be released through this embodiment of my device also is limited.

To avoid this drawback I devised another embodiment of my present device wherein a limited width of control film may be sufficient for quite a large number of scents to be selected therethrough. This embodiment is shown in a diagrammatic manner in Fig. 3.

Here, again, a light source 10 is used in connection with a parabolic reflector 11, producing the light beams or rays 12, as has been described hereinbefore.

The control or selective film 13 also is constructed entirely identically to the one described hereinbefore, and rods 56 are arranged in front thereof.

In Fig. 4 I illustrate the operation of the selective control film or tape 13, in connection with the picture film 40. The picture film is wound off a reel 40a, by an appropriate means in a projector, as it is well known in this art. A sprocket gear 41 is operated through the film 40, as by the usual perforations along the margin thereof. Through sprocket chain 42 a larger sprocket gear 43 is operated, at a greatly reduced speed, and gear 43 will move, through sprocket gear 44, the scent controlling film or tape 13, as will be understood.

In this modification I indicate a light gate 45 through which the film 13 passes, said gate having narrow lateral slots 45a, registering with the rods 56.

As the film 13 passes with an opening 13a there-of in registering relation with a respective rod 56, the light beam will be conducted through the rod on a certain photo-electric relay switch, and also amplifier, 65, will operate the same, whereby a respective solenoid 21, and solenoid valve 20, will also be operated, and the respective 75 scent conducted into the distributing ducts by

the pipe 19, similarly as has been described hereinbefore.

In this modification of my invention, I devised means whereby one unit of photo-electric cell and amplifier 65 may control a desired plurality of solenoids 21 and scents 18. For this purpose I may use so-called modulated light for operating the photo-electric cells and amplifiers 65, each scent attached to a cell 65 being activated by one type of modulated light and by no other.

The various holes or apertures 13a in one row of the control film or tape 13, will throw different modulated lights, and ultimately they will operate different solenoids 21, but they will always close the same cell and amplifier 65. Obviously, they will release different scents, as desired.

These specifically constructed combination photo-electric cells and amplifier 65, well known to those versed in this art, are placed in front of rods 56 registering with the same and producing respective amplified currents when a transparent portion of the film 13 passes a rod 56.

The currents so produced will be used in specific selector circuits to operate respective scent releasing valves.

Taking, as an example, rod 56a, the current produced by its photo-electric cell relay switch and amplifier 65a will feed circuits connected into an outgoing line 66 and into return line 67, respectively. Three such circuits, generally indicated by the numeral 68, are shown, but, obviously, different, desired and possible, numbers may be used, and into each a filter device 69 is inserted, as well as a relay 70. The filter devices 69 are well known in this art, and it will be understood that they will permit only the passing of an electric impulse produced by a light beam of predetermined frequency.

In one method to produce light beams answering in frequency to the various filters 69, I employ specific transparent portions 47 (Fig. 5) in the opaque control film 13. These portions will be elongated and will have a predetermined number of opaque transverse lines 48 therethrough set in a predetermined closeness.

It will be seen that when such a portion passes in front of a light beam 12, the beam will have a fluctuation answering to the pattern of the window 47, and such a modulated light will operate on the cell and amplifier 65 and the current so produced will be adapted to pass through a certain filter 69 only and operate only the solenoid 21 corresponding to its circuit.

In this manner almost any desired number of solenoid valves, respectively scents, may be operated through one cell and amplifier 65 and therethrough a restricted width of the control film or tape 13, and correspondingly restricted number of cells 65, may be sufficient to operate a great number of solenoids 21, and scents controlled by them, as will be understood.

The scent distributing valves 20 are operated by the solenoids 21 which are fed by a source of current 71 through the main lines 12 and 13. The respective solenoid circuits are generally indicated by the numerals 74, and they normally are open, as they include a switch device having a stationary pole 75 and resilient companion contact 76, normally spaced apart. When a relay 70 is energized, it will pull the resilient contact 76 to the stationary pole and thereby close the respective solenoid circuit.

Any modulated light when passing through the Lucite rods 56 and photo-electric cells and amplifiers 65, will result in a current of a specific fre-

quency, so that a number of various currents may be produced with each photo-electric cell and amplifier 65, but the selective filters 69 will allow only one respective current to pass therethrough and energize a respective circuit 68, whereby the respective switch 75, 76 will be closed, the corresponding valve 20 opened, releasing the scent which, in this manner, was desired to be released by the current produced by the respective modulated light.

As has been indicated in Fig. 2, and now shown for modulated light in Fig. 5, the apertures 14, respectively 47, may be made elongated and their length will then determine the length of time for which a certain scent is being released.

It also will be seen that the next photo-electric cell and amplifier 65b will also have three electric circuits 68b for three further scents. It may have a separate outgoing wire 66b, but all cells may have a common return 67.

In Fig. 6 I show still another modification of my invention, and in this case I use a preliminary light source 50 and a second selector light source 51, each having its respective parabolic reflector 50a and 51a.

A rather broad film or tape 52 passes in front of both parabolic reflectors, its narrower right hand portion 53 operating with the light source 50, and the left hand wider portion 54 operating with the reflector 51a.

Light conductive rods 55 are arranged in connection with the light source 50, and rods 56 cooperate with the light source 51. The film or tape portions 53, 54 are opaque, like in the earlier embodiment, and appropriate transparent portions or holes are provided in the tape or film portions as in the earlier embodiment (Fig. 2) cooperating with the respective rods 55, 56.

Photo-electric relay switch cells 57 are placed in registering relation with the rods 55 and are connected to oscillators 58 from which the circuit continues through conductors 59, united in a main conductor 60, and in conductors 61, all said conductors being connected into an amplifier and mixer device 62, well known in this art, and the details of which, therefore, are not shown, and the currents produced by said amplifier will be conducted into the selector light source proper 51, as by the line 63, and will return from the same as by the line 64.

Now the multiple selective operation of this embodiment of my device is as follows:

When an appropriate transparent portion or hole of the film or tape portion 53 registers with a rod 55, it will close the respective relay switch 57 starting the corresponding oscillator 58. The oscillators for the various rods 55 produce currents of various predetermined frequencies, and the current generated by the respective oscillator 58 will be amplified by the amplifier 62, and such amplified current will energize the selective light source proper 51, as will be obvious. In this manner a modulated light of a great variety of frequencies may be produced at the source 51.

These modulated lights will be used for currents of predetermined frequencies, each operating a certain scent, in an entirely identical manner as in the modification of Fig. 3.

The respective lower left hand portion of Fig. 6 indicates this arrangement and in said portion the respective numerals indicate the same parts as in Fig. 3.

The arrangement in the diagram of Fig. 6 differs only in that while here also three circuits

68 are shown for a selected cell and amplifier 65a, it is indicated that an indefinite number of circuits 68 may be fed from one cell 65, which, however, was understood with reference to the modification of Fig. 3, indeed, definitely stated, there too.

In the diagram of Fig. 6, also, no common return wire 67 is indicated for all the cells 65 as was the case in Fig. 3, this showing here is for the sake of clearness.

What I claim as new and want to protect by Letters Patent of the United States, is:

1. In a device to accompany the showing of a motion picture film with the release of scents a picture film, an opaque control film, means for moving the control film and picture film in synchronism, said control film having a plurality of spaced light-transmitting openings therein, a source of light and a reflector therefor, a plurality of spaced light-conducting rods positioned in front of said light source, said rods transmitting light axially therethrough, said control film movable between said light source and said rods, a plurality of normally closed containers each holding a scent-laden medium, a solenoid-actuated valve for each container adapted to open same, a photo-electric relay switch adjacent each

15

20

25

rod in electrical circuit with one of said valves, whereby when a light transmitting aperture passes a rod, light from said source passes axially through the latter, energizes a photo-electric relay switch and the solenoid-valve in circuit therewith, thus releasing a scent-laden medium from one of said containers.

2. The structure of claim 1, in which said light-transmitting openings are spaced laterally and longitudinally of said control film, the lateral spacing determining which one of said scent-laden mediums is to be released and the longitudinal spacing the time of such release.

EMERY I. STERN.
